UNITED STATES PATENT OFFICE.

WARREN O. COVEY, OF MARIETTA, OHIO, ASSIGNOR OF FIFTY-ONE ONE-HUNDREDTHS TO SAMUEL FREEDMAN, OF MARIETTA, OHIO.

ROTARY GAS-ENGINE.

No. 893,056.

Specification of Letters Patent.

Patented July 14, 1908.

Application filed December 21, 1906. Serial No. 348,955.

To all whom it may concern:

Be it known that I, WARREN O. COVEY, a citizen of the United States, residing at Marietta, in the county of Washington and State 5 of Ohio, have invented a new and useful Rotary Gas-Engine, of which the following is a specification.

This invention relates to rotary internal combustion engines, and has for its principal 10 object to provide an engine of very simple construction in which a series of cylinders are connected to a single crank and are mounted for bodily rotative movement around the crank axle, or shaft.

15 A further object of the invention is to provide a rotary engine of simple construction in which a plurality of cylinders are connected to a single supply through the medium of the supports by which the cylinders are carried, 20 and to secure an even distribution of power and utilize the force exerted in a portion of the cylinders on the working stroke for compressing the charges in the remaining cylinders.

25 A still further object of the invention is to provide an engine having a fixed crank shaft and a plurality of cylinders, the latter being arranged to revolve around the crank shaft while the pistons of the cylinders are connected to the crank, so that as the pistons reciprocate, the cylinders will be compelled to revolve:

With these and other objects in view, as will more fully hereinafter appear, the invention 35 consists in certain novel features of construction and arrangement of parts, herein-after fully described, illustrated in the accompanying drawings, and particularly pointed out in the appended claim, it being understood that various changes in the form, proportions, size and minor details of the structure may be made without departing from the spirit or sacrificing any of the advantages of the invention.

40 In the accompanying drawings:—Figure 1 is an elevation, partly in section, of a rotary internal combustion engine constructed in accordance with the invention. Fig. 2 is a transverse sectional view of the same on the line 2—2 of Fig. 1. Fig. 3 is an enlarged section of a portion of the engine and cylinder hub. Fig. 4 is a sectional view on an enlarged scale of a portion of one of the cylinders.

45 Similar numerals of reference are em-

ployed to indicate corresponding parts throughout the several figures of the drawings.

The frame of the engine includes a pair of standards 10, to the upper portions of which 60 is secured a fixed shaft 11 carrying a fixed crank pin 12, the shaft and crank pin being rigidly held from movement.

Mounted on the shaft are two hubs 15 and 16, the former being solid, and the latter being 65 hollow, and serving as an admission chamber for the explosive charge. The hub 16 is extended to partly embrace a fixed casing 18 having a cylindrical periphery, over which fits a stuffing box 19, in order to prevent the escape of any of the gases or other fluids, and this casing is placed in communication with a suitable source of supply, by means of a pipe 20.

Extending radially from the two hubs are 75 arms 22 and 23, the arms 22 being preferably solid, while the arms 23 are hollow and form passages through which the charges pass to the several cylinders.

The outer ends of the arms are provided 80 with journal boxes for the reception of trunnions 25 and 26 that project from the cylinders 27, said trunnions being diametrically opposed, and the trunnion 26 being hollow and placed in communication with the passage of arm 23 by means of a port 27.

In each of the hollow trunnions 26 is a ported partition 30 having a seat for a one-way check valve 31 which is normally retained in closed position by a suitable spring 90 32, the valve opening to permit the passage of the explosive charge to the cylinder and closing during the compression of such charge.

Each of the cylinders is provided with a piston 35 from which extends a rod 36, and 95 all of these rods are connected to a circular cross head 37, as will be seen on reference to Fig. 1. The rod 36 of one of the pistons is rigidly connected to the cross head, in order that rotative movement of the latter may 100 be insured, while the remaining rods are connected to the cross head by pivot pins 39 to permit the necessary freedom of movement of the cylinders while the engine is in operation.

105 The hollow trunnion of each cylinder leads to a passage 40 from which passage lead two ports 41 and 42, to the cylinder, and at a point opposite the port 42 is an exhaust port 43 through which the products of combus-

tion may escape at the end of each working stroke.

The operation of each cylinder is similar to the ordinary three port two cycle engine.

- 5 At the end of each working stroke the two ports 42 and 43 are open, the charge flowing in through the port 42, and the exhaust escaping through the port 43. During the stroke in the opposite direction, the ports 42
10 and 43 are closed and a fresh charge is sucked into the crank shaft end of the cylinder through the port 41, the valve 31 being open on this stroke, while the charge which previously entered the cylinder through the
15 port 42 is compressed. On the following working stroke, the charge in the crank shaft end of the cylinder is compressed, and valve 31 is closed, and by the time the piston reaches the end of the working stroke, the
20 charge which has been compressed in the crank shaft end of the cylinder will flow through the passage 40 and port 42 into the explosion chamber.

The explosion chamber ends of the several
25 cylinders are preferably provided with heat radiating ribs 45, and as the engine rotates, the heat will be radiated to an extent sufficient to keep the cylinders from overheating.

- I claim:—
30 The combination with a frame, of a crank shaft rigidly secured thereto and having a

crank pin, a pair of hubs mounted on the shaft at opposite sides of the crank pin and free to revolve on said shaft, one of said hubs being hollow, and the other solid, radially disposed arms extending from the hubs and provided at their outer ends with bearings, the arms of the hollow hub having passages for the explosive charges and communicating with said hollow hub, means for supplying the explosive charge to the hollow hub, cylinders, a pair of trunnions extending from each cylinder and mounted in bearings at the outer ends of the arms, one of said trunnions being hollow and having ported communication with the hollow arm, a check valve arranged in the hollow trunnion, a piston disposed in each of the cylinders, a revoluble cross head on the crank pin, a piston rod rigidly connected to the cross head and to one of the pistons, and additional piston rods rigidly connected to the remaining pistons and pivotally connected to the cross head, substantially as specified.

In testimony that I claim the foregoing as my own, I have hereto affixed my signature in the presence of two witnesses.

WARREN O. COVEY.
